(57) **CLAIM**

The ornamental design for a nasal pad for use with a respiratory mask, as shown and described.

DESCRIPTION

FIG. 1 is a perspective view of a first embodiment of my new invention;

FIG. 2 is a front view thereof;

FIG. 3 is a top view thereof;

FIG. 4 is a right side view thereof, a left side view being a mirror image thereof;

FIG. 5 is a bottom view thereof;

FIG. 6 is a rear view thereof;

FIG. 7 is a perspective view of a second embodiment of my new invention;

FIG. 8 is a front view thereof;

FIG. 9 is a top view thereof;

FIG. 10 is a right side view thereof, a left side view being a mirror image thereof;

FIG. 11 is a bottom view thereof; and,

FIG. 12 is a rear view thereof.
